UNITED STATES PATENT OFFICE.

SAMUEL E. CREECH AND PERRY BLAND, OF SULLIVAN, ILLINOIS.

DESIGN FOR A HAIR-PIN.

52,947.

Specification for Design.

Patented Feb. 4, 1919.

Application filed April 13, 1918. Serial No. 228,479. Term of patent 14 years.

To all whom it may concern:

Be it known that we, SAMUEL E. CREECH and PERRY BLAND, citizens of the United States, and residents of Sullivan, in the county of Moultrie and State of Illinois, have invented a new, original, and ornamental Design for Hair-Pins, of which the following is a specification, reference being had to the accompanying drawing, forming part thereof.

Fig. 2 is a much enlarged view of the ends of the hair pin.

We claim:

The ornamental design for a hair pin, as shown.

Signed at Sullivan, in the county of Moultrie, and State of Illinois, this 10 day of April, 1918.

SAMUEL E. CREECH.
PERRY BLAND.
